CONVERTER AND HEAT EXCHANGE
CIRCUITS THEREFOREugene J. Houdry, Haverford, Pa., assignor to
Houdry Process Corporation, Wilmington, Del.,
a corporation of Delaware

Application August 6, 1937, Serial No. 157,680

7 Claims. (Cl. 23—288)

The present invention relates to exothermic or endothermic reactions in which fluid reactants enter into synthesis, metathesis or decomposition. More particularly it has to do with control by means of heat exchange fluid of the temperature of a reaction zone within a converter in which such reactions are effected, especially when the reaction zone contains a contact mass which promotes, enters into, or in any way assists the reactions. It is concerned with the design of the converter and with circuits and apparatus for conducting one or more streams of heat exchange fluid at controlled temperature through conduits within the reaction zone.

One object of the invention is to provide apparatus of the type described, which is adapted to provide quick and easy access to the heat exchange conduits for purposes of inspection, cleaning or repairs. Another object is to facilitate removal of heat exchange conduits from the converter. Another object is to eliminate the possibility of heat exchange fluid leaking into the reaction zone to damage the converter structure or otherwise interfere with its operation. Another object is to minimize the number of conduit joints in the entire heat exchange circuit. Another object is to provide for heat transfer between the temperature control fluid and the contact mass by conduction, by radiation, or by both, in any desired proportion. Another object is to avoid stagnation of fluid reactants and/or reaction products within the reaction zone. Other objects will be apparent from the detailed description that follows.

Concrete embodiments of the invention are disclosed in the accompanying drawings, in which:

Figure 1 illustrates one form of the invention, showing in sectional elevation a converter containing heat exchange conduits as part of a circuit for heat exchange fluid, the circuit being shown partly diagrammatically and partly in sectional elevation.

Figure 2 is an arrangement similar to but generally the reverse of Figure 1, illustrating a modified heat exchange circuit and a somewhat different form of heat exchange conduits.

Figures 3 and 4 are partial vertical sectional views generally similar to Figure 1 but illustrating different types of converters and modified forms of the heat exchange circuit.

Figure 5 is a fragmentary sectional plan view on an enlarged scale of a portion of the converter shown in Figure 3 and taken substantially along

line 5—5 in the latter illustrating a slightly modified conduit arrangement; and

Figure 6 is a fragmentary view taken substantially along line 6—6 of Figure 5 shown partly in elevation and partly in section.

Referring to the drawings, in the various figures of which like or similar reference characters indicate like or similar parts, and particularly to Fig. 1, converter 7 is divided into a centrally located reaction chamber or zone 8 containing a contact mass M of any desired type and end manifolding chambers 9 and 10 by perforated partitions or grid members 11 and 12. Fluid reactants may enter one of the manifolding chambers, such as 10, as by line 13, and from such manifolding chamber be admitted to reaction zone 8 to be converted therein into reaction products, which may be discharged into manifolding chamber 9, thence to pass from the converter by connection 14.

A bath or body of low vapor pressure heat exchange fluid 16 such as molten lead, a molten alloy, a fused salt or mixture of salts, or any suitable substance which exists in liquid phase at the temperature conditions prevailing with-

in the heat exchange system is maintained in an open tank or receptacle 17 adjacent and below converter 7. Such heat exchange fluid is continuously circulated at controlled temperature in a multiplicity of substantially parallel streams 30 through reverse flow conduits, such as conduit assemblies C, extending from receptacle 17 through a wall of converter 7, as through head 19 thereof, across manifolding chamber 10 and in freely slidable relation through perforations in 35 partition 12 to traverse reaction chamber 8 and have free and closed ends E adjacent partition 11. Conduit assemblies C, being rigidly attached in fluid tight manner only to converter head 19 by joints accessible from the outside of 40 the converter structure, as through sleeves or nipples 18 by welded joints, as indicated, are insertable into and removable from converter 7 from the outside of the latter. Conduit assemblies C are preferably of the nested type comprising inner inlet members 15a extending freely and loosely into outer outlet members 15b, which latter have free and open ends in receptacle 17 preferably below the level (indicated at L) of heat exchange liquid 16, while inner mem-

bers 15a may extend beyond the lower ends of conduits 15b to be suitably arranged for receiving streams of liquid 16 at controlled temperature. As shown, receptacle 17 may be divided into upper and lower compartments by partition 55

50

55

20 provided with suitably located perforations through which conduits 15a may extend into the lower of such compartments. Conduits 15a are preferably attached to partition 20, as for example, by a bolt and flange connection, such as indicated at 25, but in some instances they may rest freely on partition 20 with any desired type of stop member being used to engage the partition and to limit the projection of the 10 conduits into the lower compartment of receptacle 17. Heat exchange liquid 16 discharged into the upper compartment of receptacle 17 may be continuously removed therefrom through line 21 having an inlet substantially at or some- 15 what below liquid level L and forced by pump 22 through a suitable heat exchange unit, indicated at 23, thence through line 24 into the lower compartment of receptacle 17 and through reverse flow conduit assemblies C to be returned to the 20 upper of the aforesaid compartments.

Quick and easy access to the interior of conduits 15b for purposes of inspection, cleaning or repairs may be gained without it being necessary to open the converter structure. To this end, 25 after stopping circulation of heat exchange fluid 16, receptacle 17 and conduit assemblies C are first drained of liquid 16, as by valved lines 26 and 27; then the flanges indicated in lines 21 and 24 are disconnected and receptacle 17 and conduit members 15a supported thereby are lowered as a unit until conduits 15a clear the lower ends of outlet conduits 15b. Conduits 15a may then be removed from partition 20, and/or receptacle 17 may be lowered further and/or moved to one 30 side, as desired, to provide the working space required or desired for the operation contemplated on conduits 15b. When it becomes necessary or desirable to remove one or more of the conduits 15b for replacement or for repairs which cannot be made by the insertion of a tool thereinto, they can easily and quickly be removed without effecting any other disassembly of the converter structure, the only steps required being disconnection of the aforementioned fluid tight joint 35 between each conduit and the wall of the converter and the actual withdrawal of the conduit from the converter. Of course, reinsertion of conduits 15b is effected as easily and expeditiously as their removal by reversing this procedure.

40 Leakage of heat exchange fluid into the converter proper results, in many instances, in the contamination of reactants, reaction products and/or of the contact mass within the reaction zone, and, in some cases, provides a serious fire or explosion hazard and/or a source of injury to equipment auxiliary to the converter. For example, when treating or converting organic fluids, such as hydrocarbons, particularly at high temperatures, leakage of a fused eutectic mixture of sodium nitrate and sodium nitrite will, in many instances, produce a fire or explosion. Should lead or molten alloy be the heat exchange fluid, leakage of such fluid within the converter may cause contamination or even effect 45 practically complete destruction of the usefulness of the contact mass contained therein. Should heat exchange fluid of either of these types be carried out of the converter along with reaction products, stoppage of auxiliary cooling equipment for such products may result. With the above described converter and heat exchange circuit it becomes possible and feasible to eliminate the above hazards, for detachable joints in the portions of the heat exchange circuit 50 located within the converter may be entirely

5 avoided simply by providing conduits 15b having closed ends E and walls which are of a single or integral part, as by forming each conduit 15b and closed end E from a single piece or billet of metal or by welding a suitable cap to a fabricated conduit.

The fact that the conduits 15a and 15b have free and open ends in receptacle 17 provides another advantage of the invention that reflects economies both in the erection and operation of 10 the converter. With the type of structure shown, conduit manifolding systems which would serve the reverse flow conduits are eliminated. Such conduit manifolds would not only require considerable expense and care in design, fabrication and 15 installation but they would also contain a large number of joints and bends; each of the joints, particularly those in a conduit manifolding system connecting outlet conduits 15b, would be a potential locus for leakage of heat exchange 20 fluid, especially when consideration is taken of the stresses which would normally occur in the conduit manifold with movement of converter parts caused by changes in temperature; each bend would cause a substantial loss in pressure of 25 fluid passing therethrough, thereby increasing the pressure necessary for forcing the heat exchange fluid through the system and augmenting the cost of circulation.

In the embodiment of the invention disclosed 30 in Figure 2, receptacle 17a for the heat exchange medium is located adjacent and above the upper head 19a of converter 1a and is provided with a perforated bottom 28 through the perforations in which reverse flow conduit assemblies C' extend downwardly into the converter to have free and closed ends E' slidably received by perforations in lower partition 12a. Outer and outlet conduit members 15b' have open ends within receptacle 17a and are attached in fluid tight manner both to the bottom 28 of the same as through sleeves or nipples 29 and to converter head 19a, as for example, through insulating sleeves 30. Heat exchange fluid 16, after being discharged from conduits 15b' into receptacle 17a, is, after the manner described in connection with Fig. 1, forced by pump 22a through the circuit comprising line 21a, heat exchanger 23a and line 24a, but, after leaving the latter and before entering inlet conduits 15a' the heat exchange fluid enters a conduit manifolding system comprising a header 31, a plurality of branched manifolds 32 supported from receptacle 17, as by beams 33 and thence enters conduits 15a' connected to and depending from branches 32 to extend freely and loosely into outlet conduits 15b'. This modification of the invention possesses the advantage that when it is desired to gain access to the interiors of conduits 15b' it is not necessary to move receptacle 17a but only to disconnect the flanges shown in one or more of the manifold branches 32 and remove each of said branches and their depending conduits as a unit. Of course, receptacle 17a needs to be drained, as through valved line 21a, and fluid 40 16 remaining in conduits 15b' displaced or pumped therefrom. When it is desired to remove conduits 15b', however, it is necessary to disconnect the joints between the same and nipples 29 before lifting receptacle 17a out of 45 the way.

Sleeves 30, shown substantially concentric with conduits 15b' and through which the latter are attached to converter head 19a, extend across manifolding chamber 8a to be slidably received 50

by perforations of suitable size in partition 11a, beyond which they are joined in fluid tight manner to conduits 15b'. They separate the reverse flow heat exchange conduit assemblies C¹ from manifolding chamber 9a and restrict the sphere of influence of heat exchange fluid 16 substantially to reaction chamber 8a by limiting the heat exchange between fluid 16 and fluids traversing manifolding chamber 9a. If desired, the 10 annular space between conduits 15b' and sleeves 30 may be filled with insulating material to further decrease such heat exchange.

Outer members 15b' of reverse flow conduit assemblies C¹ are shown with fins 43 attached thereto for providing, in known manner, heat conductive paths extending through substantially all parts of contact mass M. Such fins are of particular importance when Mass M is of such character that it cannot readily conduct heat. When the use of such extended surfaces directly attached to conduit assemblies C¹ is desired it is usually necessary to effect some disassembly of the converter proper when withdrawing the outer conduits 15b' from the same, as for example, removal of converter head 19a and partition 11a after disconnecting sleeves 30 from the former.

In the modified converter 1b illustrated by Fig. 3, reverse flow conduits C² are received by and are separated from contact mass M by outer encasing or enclosing members 34 mounted in partition 12b and extending across reaction chamber 8b to have open ends slidably received by perforations 35 in partition 11b. As shown, each of the members 34 may be perforated at intervals and may have an end opening into one of the end manifolding chambers, such as chamber 9b, to have the other end substantially sealed against fluid communication with the other of said manifolding chambers, as by the use in said other end of a suitable sealing device as perforated cap 36 which provides a sliding and substantially fluid tight joint between members 34 and conduit assemblies C². Thus, each of the members 34 40 may serve as conduits for effecting admission or distribution of reactants through or removal of reaction products from contact mass M at a plurality or multiplicity of points therein after the manner described in United States Patent No. 1,987,904 issued to me on January 15, 1935. Also, a second and complementary series of perforated conduits establishing fluid communication between the other of said manifolding chambers and interior portions of reaction chamber 8a, such as perforated conduits 37 interposed between conduit members 34 and mounted in partition 12b with an end opening into manifolding chamber 16b, may be provided for venting reaction products from or admitting reactants 50 through mass M at a plurality or multiplicity of points as indicated, for example, in United States Patent No. 2,042,468, issued to me on June 2, 1936.

When complementary inlet and outlet members, such as conduits 34 and 37 or their equivalents, are used, the resulting angular movement of fluid through reaction chamber 8b may produce, in some instances, stagnant or relatively stagnant pockets or zones therein, the number, location and extent of such zones depending upon the number and spacing of the inlet and outlet members and arrangement of perforations in these members. The number and effect of such stagnant zones may be minimized or even eliminated by providing straight through, as well as angular flow, through at least a portion of

reaction chamber 8b. To effect this, any desired part, but usually less than the predominant proportion, of the fluid reactants, may be admitted directly to reaction zone 8b without passing through distribution conduits, and/or any desired portion of the reaction products may similarly be discharged directly into the corresponding manifolding chamber. One method of obtaining the straight through flow is to provide perforations in upper and/or lower partition 11b 10 and/or 12b in addition to those required for receiving the conduit members. In the specific embodiment shown in Fig. 3 straight through flow is gained by admitting the desired portion of reactants through partition 12b 15 around the bases or mountings of encasing members 34 and by providing perforations 35 in partition 11b substantially larger than the upper ends of members 34 thereby to permit the desired amount of reaction products to flow directly into manifolding chamber 9b through the intervening spaces.

The method indicated in Fig. 3 of providing flow of fluid around the ends of conduits 34 is illustrated in detail in Figs. 5 and 6, in which 23 perforated inlet or outlet conduit 34b has an open end received in and is supported by slotted or splined insert 39 screwed or otherwise fastened in partition or tube sheet 12b. The inner surfaces of projections 38 in inserts 39 are shown 30 provided with screw threads which engage the threaded end of conduit 34b, thus providing for passage of fluid through slots or recesses 40 in addition to through conduit 34b. It is, of course, to be understood that conduit 34b may have a reverse flow heat exchange conduit extending therewithin, the showing of such a conduit in Figs. 5 and 6 having been omitted for the sake of simplicity and clarity.

In the modified circuit for heat exchange fluid 40 16 illustrated in Fig. 3 the means for adjusting the temperature of that fluid prior to forcing the same through reverse flow conduit assemblies C² are located within receptacle 17b, and may be, for example, a system of conduits 41 through 45 which a suitable heating or cooling medium is circulated. As shown, the heat exchange means may be located within the lower of a pair of compartments provided by partition 20b containing perforations through which inlet conduit 50 15a² extend in a freely slideable manner and other perforations for establishing fluid communication between said upper and lower compartments. Partition 20b serves as a baffle providing quiet and uniformly distributed flow of liquid 16 into 55 the lower from the upper of said compartments after being discharged into the latter from conduits 15b². Heat exchange fluid 16, at the adjusted temperature, is continuously withdrawn from the lower compartment and forced by pump 60 22b through the circuit comprising lines 21b, 24b and conduit manifold 32b and thence into inlet members 15a².

Heat transfer between reverse flow conduit assemblies C² and members 34 is effected substantially completely by radiation in the specific arrangement disclosed in Fig. 3, since the conduit assemblies and the encasing members are in spaced relation with each other for substantially their entire mutual extent. Such heat transfer 70 75 may be at least partially by conduction, as desired, or as required by the rate of heat transfer to or from contact mass M when due consideration is taken of the rate of circulation and temperature of heat exchange fluid 16 which pro-

vides the most favorable cost of operating the converter while effecting any particular reaction or sequence of reactions therein. In general, the closer the most suitable temperature of heat exchange fluid 16 to the temperature maintained within contact mass M the larger should be the proportion of heat transfer by conduction. One method of effecting any desired amount of heat transfer between heat exchange fluid 16 and contact mass M by direct conduction is illustrated in Fig. 4, in which reverse flow conduit assemblies C³ and outer members 34a are connected by any desired number of metallic heat conductive linkages, indicated at 42. Such linkages may be projections of suitable size and shape extending from outlet conduits 15b³ to slidably and tightly engage the inner surfaces of casings 34a or be fastened to the latter in any desired manner, as by threaded joints, bayonet locking devices or the like. Members 34a are provided with fins 43a extending into contact mass M, thus, as in Fig. 2, providing for direct conduction of heat between heat exchange fluid 16 and substantially all parts of contact mass M. It is to be noted that when fins are provided on outer casings such as members 34 or 34a of Figs. 3 or 4, it is not necessary to gain entrance to the converter structure for removal of the reverse flow heat exchange conduits. It is to be understood that extended surfaces or fins of any desired type may be used with any type of outer enclosing members, such as conduits 34 or 34a, as illustrated in Figs. 3 and 4, respectively, whether such outer enclosing members be perforated or imperforate or whether heat transfer between the contact mass and the heat exchange fluid be by radiation, by conduction or both.

Other modified forms of the invention possessing the advantages of economy, simplicity and safety of the specific embodiments disclosed and described herein will be apparent to those skilled in the art. For example, the reverse flow heat exchange conduits may extend through any wall of the converter and into a reaction zone therein, whether the heat exchange conduits are perpendicular, oblique or substantially parallel to the direction of flow of reactants and reaction products through the reaction zone, or whether or not such conduits traverse a manifolding or other chamber after passing through the shell of the converter and before entering the reaction chamber. In the event the heat exchange conduits extend through a side wall of the converter, they may enter a receptacle for the heat exchange fluid located beside the converter through a side wall of the receptacle. When reactant fluids are distributed through the reaction zone at a multiplicity of points and/or fluid reaction products removed from a multiplicity of points within the reaction zone, reverse flow heat exchange conduits adapted to effect heat transfer by conduction, by radiation or by both, may extend into the reaction zone to be entirely separate from the fluid distributing and/or outlet members.

The invention in its broad and narrow aspects has a wide range of utility in the fields of physical and chemical treatment of organic or inorganic fluids. Typical processes in which the invention is a valuable aid include: transformation or refining or high or low boiling hydrocarbons to produce motor fuels, lubricating oils or other valuable products involving, if desired, the alternate use of a contact mass in production of the desired end material and in regeneration in

place to remove combustible deposits therefrom; hydrogenation of carbon monoxide, of hydrocarbons and/or their derivatives; the purification of gases by contact masses having selective adsorptive properties and/or the ability to remove 5 impurities by chemical action; selective oxidation of hydrocarbons and/or their derivatives to produce organic acids or related compounds; synthesis of ammonia; the catalytic combustion of partially burned flue gases and the like; and 10 oxidation of sulphur dioxide to produce sulphuric acid anhydride.

I claim as my invention:

1. In combination with a converter providing a reaction chamber for containing a contact mass, means for supplying liquid in heat exchange relation with said reaction chamber comprising an open removable receptacle outside said converter and containing a body of heat exchange liquid, a series of inner and outer reverse flow conduits disposed within the reaction chamber, said outer conduits having a closed end within the converter and an open end extending through a wall of the converter into said receptacle, said inner conduits each having an open 20 end within the outer conduits and the other end connected to a manifold within said receptacle, a perforated baffle extending transversely of said receptacle between the ends of the outer conduits and said manifold for the inner conduits, heat 30 exchange means in said receptacle for controlling the temperature of fluid therein, a conduit connecting said manifold and said receptacle having pumping means therein for passing liquid at controlled temperatures through said reverse flow 35 conduits, said connecting conduit opening into said receptacle so that said perforated baffle is interposed between it and the open ends of said outer conduits.

2. In a converter for effecting chemical reactions, a pair of spaced apertured partitions dividing the converter into a reaction chamber for containing contact material and cooperating fluid manifolds, a set of perforated fluid conduits supported in one partition and extending across 45 said reaction chamber in loosely fitting engagement with the apertures of the other partition providing fluid passage through said other partition, said first-mentioned partition having apertures permitting fluid passage therethrough, a 50 second set of perforated conduits in said reaction chamber communicating with one of the manifolds and cooperating with said first set of perforated conduits for passing fluid therebetween, a series of heat exchange units extending within 55 the perforated fluid conduits of one of said sets, said units comprising inner and outer conduits in nested relation to effect reverse flow of heat exchange fluid within each unit, said outer conduits of said units being closed at one end and being secured adjacent their other and open ends to an outer wall of said converter, an open removable receptacle for heat exchange liquid positioned outside said converter having a partition 60 providing upper and lower compartments, said inner conduits of said units extending through said upper compartment and being secured in apertures in said last-named partition to communicate with said lower compartment while their other ends communicate with the interior 65 of said outer conduits of said units near the closed ends thereof, the open ends of said outer conduits of said units extending into said upper compartment of said receptacle, and a conduit 70 interconnecting said compartments and having 75

pumping means for circulating the heat exchange fluid through the nested conduits.

3. In a converter having partitions providing a reaction chamber for containing a contact mass, a series of encasing members mounted in a partition and extending substantially in parallelism across the reaction chamber to be embedded in said contact mass, a series of heat exchange units extending through a wall of said converter and within said encasing members, each unit comprising an outer conduit closed at one end and an inner conduit open at both ends in nested partly telescoped relation with said outer conduit for reverse flow movement of heat exchange fluid, said outer conduits being secured to said converter wall so as to dispose their closed ends within said encasing members and to have their other and open ends extending beyond said converter wall, heat conducting elements disposed between said outer conduits of said units and said encasing members, and a removable and open receptacle separate from said converter for containing a body of heat exchange liquid, a partition extending across said receptacle providing upper and lower compartments, said partition having apertures through which one end of each of said inner conduits extends to communicate with the lower compartment and said open ends of said outer conduits terminating above said partition within the upper compartment, and means interconnecting said compartments for circulating the heat exchange liquid through the nested conduits.

4. In a converter for effecting fluid reactions, a pair of tube sheets extending thereacross dividing the interior thereof into a centrally located reaction chamber for containing a contact mass and end manifolds, two sets of perforated conduits extending longitudinally within said reaction chamber in uniformly spaced relation, one set having open ends communicating with one manifold for admitting reactants in cross flow to said reaction chamber, and the other set having open ends communicating with the other manifold for venting reaction products from the reaction chamber, and each of said tube sheets having apertures for providing direct fluid communication between said reaction chamber and each of said manifolds, thereby to provide combined cross and straight through movement of

fluid within said reaction chamber and to avoid stagnant pockets.

5. In a converter for effecting chemical reactions, a pair of spaced apertured partitions dividing the converter into a reaction chamber for containing contact material and cooperating fluid manifolds for the reaction chamber, a set of perforated fluid conduits supported by one partition and extending across the reaction chamber in loosely fitting engagement with the apertures of the other partition but in communication with one only of said manifolds, a second set of perforated conduits extending across said reaction chamber in communication with the other only of said manifolds and cooperating with said first set of perforated conduits for passing fluid therebetween, both said partitions having apertures permitting direct passage of fluid therethrough between said chamber and said manifolds whereby said apertured partitions and said perforated conduits provide combined cross and straight through movement of fluid within the reaction chamber to avoid stagnant pockets.

6. In a converter for effecting chemical reactions, a tube sheet defining one end of a reaction chamber therein, a perforated conduit extending into said chamber for distributing fluid therethrough or venting fluid therefrom, an insert in said tube sheet securing an end of said conduit, said insert being apertured to provide for direct passage of fluid into or from said chamber through said tube sheet.

7. In a converter for effecting chemical reactions, a pair of spaced tube sheets partitioning the converter into a reaction chamber and cooperating fluid manifold chambers, perforated conduits communicating with said manifold chambers through said tube sheets for admitting reactants to the reaction chamber and for venting products of reaction therefrom, apertured inserts in one of the tube sheets for securing an end of said perforated conduits and for passing fluid directly to and from the reaction chamber, and perforations in the other tube sheet for receiving the free end of said conduits and for passing fluid directly to and from the reaction chamber.

EUGENE J. HOUDRY.
